UNITED STATES PATENT OFFICE.

MAXWELL KREPP, OF FRANKLIN, PENNSYLVANIA.

ROD-CATCHER.

No. 848,911.

Specification of Letters Patent.

Patented April 2, 1907.

Application filed October 27, 1905. Serial No. 284,689.

To all whom it may concern:

Be it known that I, MAXWELL KREPP, a citizen of the United States, residing at Franklin, in the county of Venango and 5 State of Pennsylvania, have invented certain new and useful Improvements in Rod-Catchers, of which the following is a specification, reference being had therein to the accompanying drawings.

10 My invention relates to improvements in rod-catchers, the object, construction, and operation of which is herein fully set forth, reference being had to the accompanying drawings, which form a part of this specification, and in which—

Figure 1 is a plan view of my device. Fig. 2 is a side elevation. Fig. 3 is a section on line 3 3 of Fig. 1. Fig. 4 is a section on line 4 4 of Fig. 1. Fig. 5 is an elevation of the 20 head of an oil-well and shows the way in which my device is applied to a polished rod for the purpose of catching the same.

The same reference-letters indicate identical parts in the several views.

25 In order to convey a clear understanding of the object of my device, it is necessary to set forth somewhat minutely that portion of the details of an oil-well which are above the derrick-floor, and for this purpose Fig. 5 has 30 been prepared and elucidated in such a manner as to be nearly self-explanatory. The sucker-rod of an oil-well is connected, through the medium of the polished rod, to the walking-beam, by means of which beam said rods 35 are given an up-and-down movement. Said polished rod is secured to the walking-beam by means of an adjuster, of which there are various styles; but in Fig. 5 is shown one of a common and well-known type, the general 40 form of which is that of a cross. The polished rod passes through the vertical arms of the adjuster, and the horizontal arms rest upon the walking-beam or its equivalent. A set-screw passes through one of said horizontal arms and bears against the polished rod, 45 thus securing it firmly in the adjuster.

For various reasons it often becomes necessary to readjust the polished rod in the adjuster in order to keep the plunger properly 50 located in the working barrel. When the readjusting operation becomes necessary, the walking-beam or its equivalent is brought to its highest position. The polished rod is then caught by some means and held stationary, the set-screw in the adjuster is 55 loosened, and the adjuster then slipped down

upon the rod, when the screw is again tightened at the desired point, and the readjustment is complete.

Inasmuch as the weight sustained by the 60 polished rod is in some instances several hundred pounds, it is necessary to have some strong, simple, and quickly-operated means of catching and holding the rod while the readjusting is being accomplished, and it is for 65 this purpose that my rod-catcher is devised.

The construction of my device is substantially as follows: I provide a spanner 1, which is of nearly semicircular shape, having an opening or gap 2 of sufficient width to 70 freely receive the polished rod. At a point quartering or at a right angle to said opening is seated a wedge-shaped vertically-movable jaw 3, which is actuated by the lever 4. The upward inclination of the seat of said jaw is 75 outward, so that when the outer end of said lever 4 is thrown downward the jaw 3 is raised and recedes, as shown in dotted lines in Fig. 3. The polished rod may then freely enter the opening or gap 2 of the spanner; 80 but when said lever is carried upward to a horizontal position it throws the jaw downward and inward, so that it encroaches upon the opening 2 of the spanner.

When the catcher is to be used, jaw 3 is 85 raised as aforesaid and the spanner is placed about the polished rod, resting upon the stuffing-box. When the polished rod begins to descend, lever 4 is raised, which throws jaw 3 downward and inward against said rod and 90 clamps it firmly, thus preventing its further downward movement. The contact-face of jaw 3 is knurled or roughened in order to cause it to more effectually grip the polished rod. The rod is thus held stationary while 95 the adjusting is being done, and when this is complete and the rod again raised the catcher may be easily and quickly removed.

Having thus described my invention, what I claim as new, and desire to secure by Letters Patent, is—

1. In a device of the character specified, a spanner, having a substantially semicircular gap, a vertically-movable jaw located at one side of said gap, and means of actuating said 105 jaw.

2. In a device of the character described, a spanner having an opening of substantially semicircular form, in combination with a downwardly and inwardly moving jaw, located at one side of said opening, and means of actuating said jaw.

3. In a device of the character described, a spanner having a gap, an inclined seat at one side of said gap, a wedge-shaped jaw, movably seated in said seat.
4. In a device of the character described, a spanner, having a gap as shown, an inclined seat at one side of said gap, and a movable jaw in said seat.
5. In a device of the character described, a spanner having a gap, an inclined seat at one side of said gap, a wedge-shaped jaw, movably seated in said seat.

In testimony whereof I affix my signature in presence of two witnesses.

MAXWELL KREPP.
